UNITED STATES PATENT OFFICE.

JAMES SAYIH, OF BROOKLYN, NEW YORK.

AMUSEMENT DEVICE.

1,399,582.

Specification of Letters Patent.

Patented Dec. 6, 1921.

Application filed October 25, 1920. Serial No. 419,343.

To all whom it may concern:

Be it known that I, JAMES SAYIH, a citizen of Syria, and a resident of the city of New York, borough of Brooklyn, in the county of Kings and State of New York, have invented a new and Improved Amusement Device, of which the following is a full, clear, and exact description.

This invention relates to amusement devices and has particular reference to carousels adapted to be installed in amusement parks.

The invention contemplates and has for its principal object to provide a highly amusing and extremely attractive device which is comparatively simple and inexpensive in construction and operation, inexpensive to manufacture and install and which includes the features of strength and durability.

Another object of the invention is to provide an amusement device of the carousel type which includes a plurality of annular series of cars and means for driving the same in circular undulating paths and in opposite directions whereby to impart to the riders a new and amusing sensation.

A still further object of the invention is to provide an amusement device of this character which includes a plurality of series of movable cars with means for driving each alternate series of cars in opposite directions and each series at different rates of speed whereby the riders may have a choice of selection at a speed at which they desire to travel.

With the above recited and other objects in view, the invention resides in the novel construction, combination and arrangement of parts, set forth in the following specification, pointed out in the appended claims and illustrated in the accompanying drawings, in which—

Figure 1 is a plan view of the device.

Fig. 2 is a side elevation thereof.

Fig. 3 is an enlarged sectional view taken therethrough approximately on the line 3—3 of Fig. 1.

Fig. 4 is a fragmentary sectional view taken approximately on the line 4—4 of Fig. 1.

Fig. 5 is a fragmentary sectional view taken approximately on the line 5—5 of Fig. 3.

Fig. 6 is a detail fragmentary perspective

view of the connection between one of the 55 tractor arms and the driving means.

Referring to the drawings by characters of reference, 10 designates a stationary circular run-way having inner and outer vertical side walls 11 and 12 and a cover wall 13 connecting the same. The top wall is undulated to constitute a series of elevations over which the cars 14 are adapted to travel. The cover wall is provided with a plurality of concentric circular slots 15 which establish 60 communication to the interior of the run-way. A plurality of transverse beams 16 are supported in parallel relation to the cover wall 13 within the confines of the walls 11 and 12 of the run-way by the vertical standards 17 and a plurality of circular rails 18 are secured to and bear upon the upper surface of the beam 16, one of each of said rails being disposed directly beneath each of the slots 15. A plurality of concentric channel 70 frames 19 are mounted for relative rotation on each of the rails 18 by means of the wheels 20 which are journaled in the depending brackets 21. An annular series of cars are adapted to be connected to each of 80 the channel frames 19 by means of the tractor arms 22 which extend through the slots 15. Each arm 22 has a wrist pin connection 23 with the underside of its respective car and is bifurcated at its opposite end 85 as at 24 to provide the apertured knuckles 25 which are received between the spaced knuckles 26 of a bracket 27 secured to the upper side of the channel members 19. The center knuckle 26 is provided with an upstanding 90 integral lug 27 which is adapted to co-act with the bifurcated extremity 24 whereby to limit the upward swinging movement of the tractor arm to prevent the swinging of the same to a vertical position. Each of the cars 95 is provided with depending legs 28 having bearing rollers 29 which engage the upper surface of the cover wall 13 and straddle the slots 15. It will be obvious from this arrangement that rotation of the channel members 19 will draw cars 23 around the run-way, the connection therebetween serving to permit the same to raise and lower in conformity with the undulations in the upper surface of the cover wall. It is also apparent 100 that the lug 27 will serve to prevent the momentum of the cars when the frames 19 are stopped, from advancing the wrist pin

105

connection 23 past the knuckle connection at its opposite end.

The mechanism for driving the alternate series of cars in opposite directions comprises 5 a vertical stub shaft 30 mounted between each of the frames 19. A master gear 31 is keyed to each stub shaft and meshes respectively with the gears 32 and 33 keyed to the counter shafts 34 and 35 which are 10 mounted on diametrically opposite sides of the stub shafts 30. A second gear 36 is keyed to each of the counter shafts 34 and 35 and the same mesh with the annular rack bars 37 secured in the confronting open sides of the 15 channel frames 19. Each stub shaft has keyed to its lower extremity a beveled pinion 38 which meshes with a beveled gear 39 on a common drive shaft 40 having a driven pulley 41 secured thereon and over which the drive belt 42 is trained. The belt 42 is further trained over the drive pulley 43 of a power plant 44. From this construction it will be seen that rotation of the drive shaft 40 will effect simultaneous rotation 20 of the stub shafts 30 in the same direction and through the gears 31, 32, 33, 36 and the racks 37, each alternate frame 19 will be driven in opposite directions to effect movement of each alternate series of cars 25 in opposite direction at various rates of speed for the reason that the outer series of cars is compelled to travel a greater distance than the inner series. In order to provide means to permit the riders to gain 30 access to the cars, the outer side wall 12 is provided with an entrance door 45 and a stairway 46 is arranged in the space in the center of the run-way where the riders may ascend to board the various cars. The 35 cars may be constructed to simulate any animal or vehicle desired and the same are preferably provided with a cock pit 47 having a seat 48.

While there has been illustrated and de- 45 scribed a single and preferred embodiment of the invention, it is understood that the right is reserved to others than those actu- ally illustrated herein; to the full extent indicated by the general meaning of the 50 terms in which the claims are expressed and by variations in the phraseology of the same.

I claim:

1. In an amusement device, a stationary 55 annular run-way having an undulating sur- face provided with concentric annular slots, a plurality of concentric circular rows of cars movable thereover, a common means for driving the same in opposite directions, swinging means for connecting the cars to 60 the driving means through said slot to com- pensate for the relative vertical movements of the cars with respect to the driving means,

and means for preventing the advancement of the cars beyond their connection with the driving means.

2. An amusement device of the carousel type, comprising a stationary circular housing including inner and outer walls and an undulating cover wall having a plurality of concentric slots, a plurality of circular tracks 70 supported within said housing and respectively disposed beneath each slot, a plurality of circular frames mounted respectively on each track for relative rotation with respect thereto, mechanism for driving each alter- 75 nate frame in opposite directions, a plurality of rows of cars, and a swinging tractor connection between each car and its respective frame, said tractor connections extending through the slots. 80

3. An amusement device of the carousel type, comprising a stationary circular housing including inner and outer walls and an undulating cover wall having a plurality of concentric slots, a plurality of circular tracks 85 supported within said housing and respectively disposed beneath each slot, a plurality of circular frames mounted respectively on each track for relative rotation with respect thereto, mechanism for driving each alter- 90 nate frame in opposite directions at various rates of speed, a plurality of rows of cars, and a swinging tractor connection between each car and its respective frame, said tractor connections extending through the slots. 95

4. An amusement device comprising a sta- 100 tionary runway having an undulating sur- face provided with parallel slots, a plurality of cars, movable actuating members disposed beneath each slot, a common means for driv- 105 ing said actuating members, a rigid tractor connection pivoted respectively at its oppo- site ends to an actuating member and a car and extending through said slots, and means for preventing the advancement of the cars beyond the connection of the tractor member with the actuating member.

5. An amusement device comprising a sta- 110 tionary runway having an undulating sur- face provided with parallel slots, a plurality of cars, movable actuating members disposed beneath each slot, a common means for driv- 115 ing said actuating members, a rigid tractor connection pivoted respectively at its oppo- site ends to an actuating member and a car and extending through said slots, and means for preventing the advancement of the cars beyond the connection of the tractor member with the actuating member, said means comprising a lug secured to the actuator 120 member and adapted to coact with the tractor member.

JAMES SAYIH.
